UNITED STATES PATENT OFFICE.

FRANK VINCENT BRACH, OF CHICAGO, ILLINOIS.

DETACHABLE CUFF.

1,391,094.

Specification of Letters Patent. Patented Sept. 20, 1921.

Application filed January 9, 1920. Serial No. 350,286.

To all whom it may concern:

Be it known that I, FRANK VINCENT BRACH, a citizen of the United States, and a resident of the city of Chicago, county of Cook, and State of Illinois, have invented 5 certain new and useful Improvements in Detachable Cuffs, of which the following is a specification.

My invention relates to improvements in 10 detachable cuffs, and has for its object the provision of a simple and efficient construction of this character whereby the cuff will be nicely held in place, and the fact that it is detachable, largely if not entirely, 15 concealed.

Other objects will appear hereinafter.

The invention consists in the combinations and arrangements of parts hereinafter described and claimed.

20 The invention will be best understood by reference to the accompanying drawings forming a part of this specification, and in which,

Figure 1 is a view of the end of a shirt 25 sleeve provided with a cuff embodying the invention,

Fig. 2 is an internal view of the cuff and sleeve opened and flattened out,

Fig. 3 is a plan view of the cuff detached, 30 and

Fig. 4 is a section taken on line 4—4 of Fig. 2.

The preferred form of construction, as 35 illustrated in the drawings, comprises a detachable cuff consisting of the outer and inner portions 5 and 6 foldable on the line 7 to constitute a double or turn over cuff, the portions 5 and 6 being provided with the usual cuff button holes 8 arranged to register when the cuff is so folded, and adapted to receive the ordinary cuff button 9 in the usual manner. Arranged at the inner corners of the inner side portion of the cuff, thus formed, are two substantially triangular flaps 10 stitched to the cuff along the edges 11, but free therefrom along the edges 12, thus forming substantially triangular pockets open on their inner edges and each pocket is provided with a button hole 13, as 45 shown. A securing flap 14 is also secured to the inner central portion of the inner side of the cuff, being stitched there-to along the

edge 15, but otherwise free, said flap being provided with a button hole 16, as shown. The sleeve of the shirt is provided with the 55 usual cuff band 17, arranged and adapted to have its outer corners or ends fit into the pockets formed by the flaps 10 and its central portion fitted under the flap 14, as shown in Fig. 2. The cuff band is provided with button holes at its central portion and at its ends, adapted to register with the button holes 13 and 16 in the pockets 10 and the flap 14 of the cuff, when in position on the band, and ordinary collar buttons 18 60 are passed through these registering button holes, thus securing the cuff in position on the sleeve of the shirt. In this way the cuff is securely held in place on the shirt sleeve, and the fact that it is detachable, largely if 65 not entirely, concealed and hidden.

While I have illustrated and described the preferred form of construction for carrying my invention into effect, this is capable of variation and modification, without departing from the spirit of the invention. I, therefore, do not wish to be limited to the precise details of the construction set forth, but desire to avail myself of such variations and modifications as come within the scope 70 of the appended claims.

Having described my invention, what I claim as new and desire to secure by Letters Patent is:

1. In combination, a shirt sleeve provided 85 with a cuff band, said cuff band being provided at its ends with buttonholes; a cuff having substantially triangular pockets at its inner corners adapted to fit over the outer corners of the cuff band, said pockets being provided with buttonholes adapted to register with the buttonholes in the ends of the cuff band; and buttons detachably securing the cuff band in said pockets, substantially 90 as described.

2. In combination, a shirt sleeve provided 95 with a cuff band, said cuff band being provided at its ends with button holes and with a button hole situated substantially centrally thereof; a cuff having substantially 100 triangular pockets at its inner corners adapted to fit over the outer corners of the cuff band, said pockets being provided with button holes adapted to register with the

button holes in the ends of the cuff band; a flap at the inner central portion of said cuff adapted to fit over the central portion of the cuff band, said flap having a button hole 5 adapted to register with the central button hole of said cuff band; and buttons detachably securing the cuff band in said pockets and to said flap, substantially as described.

In testimony whereof I have signed my name to this specification in the presence of 10 the subscribing witness.

FRANK VINCENT BRACH.
